(57) CLAIM

The ornamental design for a "boot," as shown and described.

DESCRIPTION

FIG. 1 is a perspective view of a boot showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view thereof defined by the circled broken line indicated by 8 on FIG. 1;

FIG. 9 is an enlarged view thereof defined by the circled broken line indicated by 9 on FIG. 1;

FIG. 10 is an enlarged view thereof defined by the broken line circled on FIG. 2; and,

FIG. 11 is another perspective view thereof.

The broken lines depict environment that forms no part of the claimed design.
